(57) **CLAIM**

The ornamental design for an aromatherapy nebulizer, as shown and described.

DESCRIPTION

FIG. 1 is a top perspective view of an aromatherapy nebulizer showing my new design;

FIG. 2 is a bottom perspective view thereof;

FIG. 3 is a front elevational view thereof;

FIG. 4 is a rear elevational view thereof;

FIG. 5 is a left side elevation view thereof, with a right side elevation view being a mirror image thereof;

FIG. 6 is a top plan view thereof; and,

FIG. 7 is a bottom plan view thereof.

The broken lines are for the purpose of illustrating portions of the aromatherapy nebulizer that form no part of the claimed design.

1 Claim, 7 Drawing Sheets(56)
